OLAF HALVORSEN AND SAMUEL F. KIESLING, OF CHICAGO, ILLINOIS

SPINDLE STRUCTURE FOR TYPE HOLDERS AND THE LIKE

Application filed November 29, 1929. Serial No. 410,628.

This invention relates to certain novel improvements in spindle structures for type holders and the like and has for its principal object the provision of an improved construction of this character which will be highly efficient in use and economical in manufacture.

The salient object of our invention is to provide a spindle structure for type holders and the like that will embody an arrangement which will permit the type holder to be disposed in various angular positions with respect to the work mounted on the table of the machine with which the type holder is associated.

Another object of the invention is to provide a construction of the above described type which will permit expeditious removal of the type holder or the like from the spindle when so desired.

Other objects will appear hereinafter. The invention consists in the novel combination and arrangement of parts to be hereinafter described and claimed.

The invention will be best understood by reference to the accompanying drawing, showing the preferred form of construction and in which:

Fig. 1 is a front elevational view of a machine of the character with which the preferred embodiment of our invention is to be associated;

Fig. 2 is a fragmental side view, drawn to an enlarged scale, in which certain portions are broken away, and which shows a preferred embodiment of our invention; and

Fig. 3 is a sectional detail view taken substantially on the line 3-3 of Fig. 2.

In the accompanying drawing wherein a preferred form of construction for our invention is illustrated, 10 indicates the base of our improved machine. Extending upwardly from the base 10 is a supporting column 11 which has at the upper end thereof a supporting arm 12 which extends at right angles to the column 11. Adjustably mounted on the column 11 is a sleeve 13 which has portions 14 projecting therefrom on which a work supporting table 15 of approved form is mounted. At the free end of the arm 12 a sleeve 16 is provided and this sleeve 16 is

aligned with the work receiving table 15. Extended through this sleeve 16 is a spindle 17 which has a groove 18 therein that is engaged by screws 19 carried in the sleeve 16 in order that turning of the spindle in the sleeve 55 will be prevented. Opposite the groove 18 on the spindle 17 are rack teeth 20, which rack teeth engage a pinion mounted interiorly of the sleeve and arm 12 on the shaft 21. An operating handle 22 extends through the 60 shaft 21 and by moving the handle 22 rotative movement may be imparted to the shaft 21, which in turn will be transmitted to the rack teeth 20 in order that the spindle 17 may be moved axially through the sleeve 16 toward 65 and away from the work receiving table 15. While the foregoing is a preferred form of construction with which our invention may be associated it is to be understood that this is capable of variation and modification without departing from the purview of our invention.

As best illustrated in Fig. 2 a recess 23 is provided at the lower end of the spindle 17 which extends thereinto for a predetermined 75 distance. We have set forth that our invention is preferably associated with type holders or the like but it is to be understood that other analogous tool supporting members or tools might be used in the device 80 without departing from the spirit and scope of the invention. However, in the present instance we have shown a type holder and such a type holder is generically indicated by 85 24. The type holder 24 has extending upwardly therefrom a stud 25 and the stud 25 is intended to be extended into the recess 23. A peripheral groove 26 is formed in the stud 25 and defines a shoulder 27. A screw 28 is mounted in an opening 29 in the spindle 17 90 and this opening 29 is preferably aligned with the groove 26 when the stud 25 is disposed in the recess 23. It is, therefore, manifest that the screw 28 may be run inwardly and be disposed in the groove 26. By 95 reason of the weight of the type holder 24 it is manifest that the same will tend to move the stud 25 from the recess 23. This will be prevented by engagement of the shoulder 27 with the screw 28. The screw 28 has a rod 100

30 extended therethrough at right angles to the extent of the screw 28 which provides a gripping portion to facilitate turning of the screw 28. In addition to the rod 30, a 5 tool grip 31 is provided on the outer end of the screw 28 which may be also utilized in the turning thereof.

It is manifest that engagement of the screw 28 with the shoulder 27 will prevent removal 10 of the stud 25 from the recess 23. Retraction of the screw 28 from the groove 26 will manifestly permit the stud 25 to be withdrawn from the recess 23 and in this manner the type holder may be expeditiously detached from the spindle 17. It is also apparent that when the screw 28 is run inwardly 15 into engagement with the bottom of the groove 26 that the stud 25 may be secured against movement in any direction. However, when the screw 28 is moved from engagement with the bottom of the groove 26 but is retained in engagement with the shoulder 27, it is manifest that the stud 25 will be held against removal from the spindle 17 but 20 also that the stud 25 may be rotated relative to the spindle 17 and, therefore, the type holder 24 may be arranged in various angular positions with respect to the axes of the work receiving table 15 and it is also apparent that 25 after the type holder 25 has been moved into these angular positions that the screw 28 may again be engaged with the bottom of the groove 26 to lock the stud 25 against further movement.

35 It is manifest from the foregoing description that we have provided an arrangement for associating a type holder or the like with a spindle which will permit expeditious removal of the type holder from the spindle 40 and one which will also permit the type holder or the like to be disposed in various angular positions with respect to the spindle.

While we have illustrated and described the preferred form of construction for carrying our invention into effect, this is capable 45 of variation and modification, without departing from the spirit of the invention. We, therefore, do not wish to be limited to the precise details of construction set forth, but 50 desire to avail ourselves of such variations and modifications as come within the scope of the appended claims.

Having thus described our invention what we claim as new and desire to protect by

55 Letters Patent is:

1. In combination with a spindle, a type holder having a stud extending therefrom; means carried by said spindle for holding said stud against removal from said spindle 60 while permitting rotative movement of said stud relative to said spindle, said means being capable of being engaged with said stud to prevent movement thereof.

2. In combination with a spindle having a 65 recess in one end thereof, a type holder having

a stud projecting therefrom having a groove in the periphery thereof, said stud being disposed in said recess, and means carried by said spindle for extension into said groove to retain said stud in said recess.

3. In combination with a spindle having a recess in one end thereof, a type holder, a stud extending from said type holder having a groove in the periphery thereof, said stud being disposed in said recess, and a screw carried by said spindle extending into said groove to retain said stud in said recess while permitting rotative movement of said stud relative to said spindle, said screw being engaged by the bottom of said groove to secure 70 said stud against movement.

4. In combination with a spindle having a recess in one end thereof, a type holder, a stud projecting from said type holder, said stud having a groove therein extending around the periphery thereof, said stud being disposed in said recess, and means carried by said spindle for extension into said groove to retain said stud in said recess, said means being adapted for simultaneously preventing longitudinal movement of said stud from said recess while permitting said stud to be rotated relative to said spindle.

5. In combination with a spindle having a recess in one end thereof, a type holder, a stud projecting from said type holder, said stud having a groove therein extending around the periphery thereof, and defining a shoulder on said spindle, said stud being disposed in said recess, and means carried by said spindle for extension into said groove to retain said stud in said recess, said means being adapted when engaged with said shoulder for simultaneously preventing longitudinal movement of said stud from said recess while permitting 95 said stud to be rotated relative to said spindle.

In testimony whereof we affix our signatures.

OLAF HALVORSEN.
SAMUEL F. KIESLING.
